CLAIM

The ornamental design for a below top of wall ventilation screed device, as shown and described.

DESCRIPTION

FIG. 1 is a top elevation view of the below top of wall ventilation screed device;

FIG. 2 is a front view of the below top of wall ventilation screed device;

FIG. 3 is a back view of the below top of wall ventilation screed device;

FIG. 4 is a left side view of the below top of wall ventilation screed device;

FIG. 5 is a right side view of the below top of wall ventilation screed device;

FIG. 6 is a top side view of the below top of wall ventilation screed device;

FIG. 7 is a bottom side view of the below top of wall ventilation screed device; and,

FIG. 8 is an elevation view of the back side of the below top of wall ventilation screed device.

The broken lines in FIGS. 1-4, 6, and 8 represent portions of the below top of wall ventilation screed device that form no part of the claimed design.

1 Claim, 5 Drawing Sheets
